UNITED STATES PATENT OFFICE

2,461,050

LOOSE-LEAF BINDER

Joseph A. Gibson, Kimball, Nebr.

Application September 21, 1945, Serial No. 617,829

3. Claims. (Cl. 129—11)

1

This invention relates to a loose leaf binder, more particularly of the type known as an arch lock binder, and has for its principal object the provision of a neat, simple, and highly efficient device which can be quickly and easily opened to receive sheets, quickly and easily closed to hold the sheets in place, and which will be self-locking in the closed position so that it cannot be accidentally opened to release the sheets.

Other objects and advantages reside in the detail construction of the invention, which is designed for simplicity, economy, and efficiency. These will become more apparent from the following description.

In the following detailed description of the invention, reference is had to the accompanying drawing which forms a part thereof. Like numerals refer to like parts in all views of the drawing and throughout the description.

In the drawing:

Fig. 1 is a perspective view illustrating the improved arch lock binder in place on a backing board;

Fig. 2 is a front view of the improved binder;

Fig. 3 is a cross-section therethrough, taken on the line 3—3, Fig. 2, illustrating the binder in the unlocked or partially closed position;

Fig. 4 is a similar view illustrating the binder in the fully closed and locked position;

Fig. 5 is a similar view illustrating the binder in the open position;

Fig. 6 is a rear view of the improved binder; and

Fig. 7 is a detail view illustrating the construction of the locking member of the improved binder.

This invention is more particularly designed as an improvement over the arch file illustrated in applicant's Patent No. 2,207,192, which issued July 9, 1940.

The improved binder is designed for attachment to a backing board 10 by means of suitable attachment screws 11. The binder comprises a base plate 12, the upper edge of which is turned at right angles to form a horizontal aligning flange 13 which overlaps the upper edge of the board 10. An opening 14 is provided in the plate 12 and backing board 10 for hanging purposes.

Two bearing plates 15 having outwardly flanged bottom edges are riveted in spaced-apart relation to the base plate 12 by means of suitable rivets 16. A crank shaft 17 is rotatably mounted in the plates 15 and extends therebetween, terminating in an angularly-turned handle 18. The crank portion of the crank shaft 17 supports an elongated locking member 19. The extremities of the locking member 19 are turned outwardly to form ears 20 through which the shaft 17 passes.

The member 19 is perforated to slidably receive two hooked arch members 21. The arch members 21 are secured to, and project from, a rotatable channel member 22. Each hook member extends through one flange of the channel member 22, thence is turned outwardly and secured by rolling back the extremity of the other flange of the channel member, as shown at 23, to form a projecting pivot pin 24. Thus the wire or rod which is used to form the arch member 21 serves a double purpose in providing the pivot pins 24. The pins 24 extend through bearing openings in the plates 15 below the crank shaft 17.

The extremities of the arch members 21 coact with posts 25 to form the complete binder enclosure. The posts 25 are formed by bending a U-shaped rod at right angles to form an inverted V-shaped back portion 26. The extremities of the rod are forced through receiving openings in the back plate 12 to form the posts 25 and the base portion 26 thereof is welded or otherwise secured to the back of the back plate 12 to rigidly support the posts. The backboard 10 may be recessed to receive the portion 26 if desired.

To open the arch member 21, the handle is swung outwardly. This causes the locking member 19 to slide along and lift the arch members 21, as shown in Fig. 5. To close the arch member 21, the handle 18 is swung inwardly, thus causing the crank shaft 17 to push the locking member downward to close the arch members 21 to the position of Fig. 3.

To lock the arch members, the handle 18 is forced further inward, causing the extremities of the arch members to contact the ends of the posts 25. Further movement forces the latter 40 extremities against the tops of the posts 25 so as to flex or bend the arch members until the crank portion of the crank shaft 17 and the locking member 19 to pass their aligned or dead center position, as indicated by the center lines A and B, respectively, in Fig. 4, with the locking member 19 lying against the flange of the channel member 22. Further movement is impossible, since the crank shaft cannot pass the locking member, and return movement is prevented due to the "past dead center position" of the crank 45 17 and the locking member 19. The file is therefore securely locked until the handle 18 is again pulled outwardly to flex the arch members past the locking point.

While a specific form of the improvement has

been described and illustrated herein, it is desired to be understood that the same may be varied, within the scope of the appended claims, without departing from the spirit of the invention.

Having thus described the invention, what is claimed and desired secured by Letters Patent is:

1. A loose leaf binder comprising: a base plate; leaf-receiving posts projecting from said plate; a pair of spaced bearing plates projecting from said plate; a rotatable channel member extending between said plates; pivot pins projecting from the extremities of said channel member through said bearing plates, said pins being placed adjacent one longitudinal edge of said channel member; arch members projecting from the other longitudinal edge of said channel member in alignment with said posts; an independently rotatable crank shaft extending transversally of said arch members; and means for transmitting the eccentric motion of said crank shaft to said arch members for rotating said channel member on its pivot pins.

2. A loose leaf binder comprising: a base plate; leaf-receiving posts projecting from said plate; a pair of spaced bearing plates projecting from said plate; a rotatable channel member extending between said plates; pivot pins projecting from the extremities of said channel member through said bearing plates, said pins being placed adjacent one longitudinal edge of said channel member; arch members projecting from the other longitudinal edge of said channel member in alignment with said posts; a locking member having perforations slidably receiving said arch members; and a crank shaft extending between said bearing plates and having a crank portion supporting said locking member so that rotation of said crank shaft will cause said lock-

ing member to swing said arch members toward and away from said posts.

3. A loose leaf binder comprising: a base plate; leaf-receiving posts projecting from said plate; a pair of spaced bearing plates projecting from said plate; a rotatable channel member extending between said plates; pivot pins projecting from the extremities of said channel member through said bearing plates, said pins being placed adjacent one longitudinal edge of said channel member; arch members projecting from the other longitudinal edge of said channel member in alignment with said posts; a locking member having perforations slidably received said arch members; a crank shaft extending between said bearing plates and having a crank portion supporting said locking member; and a handle for rotating said crank shaft, the throw of the crank portion of said crank shaft and the spacing between the axis of said pivots and the axis of said crank shaft being such that said locking member will lie against said channel member when said crank shaft has been rotated beyond its extreme closing position to lock said arch members against said posts.
